UNITED STATES PATENT OFFICE.

BENJAMIN P. AUTREY, OF PILOT POINT, TEXAS.

RAILROAD-TIE.

1,321,877.

Specification of Letters Patent.

Patented Nov. 18, 1919.

Application filed July 21, 1919. Serial No. 312,154.

To all whom it may concern:

Be it known that I, BENJAMIN P. AUTREY, a citizen of the United States, residing at Pilot Point, in the county of Denton and State of Texas, have invented a new and useful Railroad-Tie, of which the following is a specification.

This invention relates to railroad ties and has for its object the provision of a tie 10 that will permit a certain amount of resiliency and in which the tension of the resilient members may be adjusted.

Another object is to provide a tie the body of which may be made of pressed 15 metal to form a housing for the resilient member.

A further object is the provision of means for inspection and repair of the resilient member without removing the tie from the 20 roadbed and to provide a simple strong and efficient tie that may be manufactured and placed on the market at a comparatively small cost.

With these and other objects in view as 25 will appear as the description proceeds the invention resides in the novel combination and arrangement of parts shown in the drawing, and specifically pointed out in the appended claim, it being understood that 30 minor changes may be made in the device without departing from the spirit or sacrificing any of the advantages of the invention.

In the drawing:—

35 Figure 1 is a side elevation, partly in section of a tie constructed in accordance with my invention;

Fig. 2 is a plan view of the same, there being parts in section;

40 Fig. 3 is a perspective view of a spring support used in conjunction with the tie; and

Fig. 4 is an end elevation of the tie.

Referring to the drawing by numerals of 45 reference in which like characters refer to like parts throughout the several figures, there is shown a housing 1 comprising upper and lower members 2 and 3, the lower member 3 forming a base for the tie and 50 consisting of a U-shaped member having upstanding side walls 4 and a bottom 5. Stiffening ribs 6 are formed on the side walls 4.

The upper member 2 is similar to the lower member, it being of slightly greater 55 width to fit over the lower member. Ribs 7 are formed on the walls of the part 2

and fit over the ribs 6. The ribs 6 and 7 serve not only as stiffening ribs but, interengaging as they do, prevent relative longitudinal movement of the parts 2 and 3. 60

Formed on the side walls of the member 2 at the ends thereof are flanges 8. Between the flange 8 and the ends of the side walls 4 are slidable end closure plates 9.

A group of coil springs 12 are located 65 preferably under each rail seat. There are four shown in the present instance and are adapted to be placed under stress between the upper housing member and a spring seat plate 13. A retaining socket 14 is formed 70 on the plate 13 for the group of springs by riveting or otherwise securing to the base member 13 a plurality of upstanding strips 16, the strips 16 being curved to conform to the diameter of the spring coil and 75 the springs being of such size and so arranged that they occupy the space between the side walls and are supported in an upright position by the said walls and the strips 16. 80

Bolts 17 connect the two members of the tie together and also provide for adjustment of the springs to the desired compression. The bolts 17 at the ends of the tie pass through the base 13 of the spring support to hold the same in position. 85

When it is desired to inspect the springs the closure 9 may be removed and should repair be necessary to any of the springs the entire spring structure may be readily 90 removed by first removing the bolt 17. A flange 18 is formed on the base member 13 to facilitate removal of the spring assembly.

The rail 19 is secured to the upper member 2 by means of a fixed rail clip 20 riveted to the tie, which engages one flange of the rail, the opposite flange being engaged by a rail clip 21, the same being movable longitudinally in a guide member 22 also riveted to the tie. A wedge block 95 23 forces the clip into engagement with the rail and effectually grips the same to the tie. Set screws 24 and 25 hold the wedge 23 and clip 21 respectfully against becoming loose. 100

A tie constructed in accordance with this invention may be easily manufactured by either casting the housing members or forming them from sheet metal. In either case assembly of the tie is easy and it is possible 110 to vary the tension on the springs to obtain any degree of resiliency desired. 105

Having thus described the invention what is claimed is:—

In a rail tie, upper and lower U-shaped housing members, having open ends, a closure plate for the said ends, interengaging ribs formed on the side walls of the two members, a resilient member comprising a plurality of springs interposed between the upper and lower members, means for re-

taining the springs in position and means for adjusting the resiliency of the springs.

In testimony that I claim the foregoing as my own, I have hereto affixed my signature in the presence of two witnesses.

BENJAMIN P. AUTREY.

Witnesses:

FRED R. WILSON,
GREEN FLAKE.
